UNITED STATES PATENT OFFICE.

LEONARD LOOP, OF TULSA, OKLAHOMA.

POLISH-ROD SUPPORT.

Application filed October 6, 1925. Serial No. 60,926.

To all whom it may concern:

Be it known that I, LEONARD LOOP, a citizen of the United States, residing at Tulsa, in the county of Tulsa and State of Oklahoma, have invented a new and useful 5 Polish-Rod Support, of which the following is a specification.

The present invention relates to a connecting member especially designed for use in 10 connecting a polish rod to a pump beam, novel means being provided for adjusting the polish rod with respect to the valve members that operate below the polish rod.

A further object of the invention is to 15 provide a device of this character which will permit of an adjustment of the polish rod, eliminating the necessity of employing beam hangers which often allow the polish rod to drop, necessitating the loss of time to re- 20 cover the same.

A still further object of the invention is 25 the provision of means whereby an adjustment may be readily and easily made, eliminating any possibility of the polish rod slipping into the well.

With the foregoing and other objects in 30 view which will appear as the description proceeds, the invention resides in the combination and arrangement of parts and in the 35 details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view illustrating 40 a connecting member constructed in accordance with the invention and illustrating one end of a pump beam.

Figure 2 is a perspective view of the adjusting member.

Figure 3 is a sectional view taken on line 3-3 of Figure 1.

Figure 4 is a sectional view taken on line 4-4 of Figure 3.

Figure 5 is a sectional view taken on line 5-5 of Figure 3.

Figure 6 is a sectional view taken on 50 line 6-6 of Figure 3.

Referring to the drawings in detail, the reference character 5 indicates a pump beam which is of the usual construction and is provided with bearing members 6 formed

with cut out portions to accommodate the 55 cross arm 7 forming a part of the connecting device.

The cross arm 7 is formed at the upper end of the reduced portion 8 of the connection and is held in position by means of 60 the threaded shank 9 of the eye member 10 that passes through a suitable opening in the head 11 of the reduced portion 8. This connecting member includes an elongated body portion having its front and rear walls 65 out away defining guide members 12 between which the adjusting member to be herein-after more fully described, moves.

Positioned at a point substantially intermediate the ends of the body portion are 70 the bearing blocks 13 which are held together by means of bolts 14, the bearing blocks 13 being secured in position on the body portion in any suitable and well known manner. The reference character 15 indicates a feed sleeve which is provided with 75 a peripheral groove defining spaced flanges 16 that operate on opposite sides of the bearing blocks 13 to permit of rotary movement of the sleeve 15 but insure against movement 80 of the feed sleeve 15 longitudinally of the body portion.

The lower portion of the feed sleeve 15 is threaded to receive the upper threaded end of the tubular member 17, while the lower 85 end of the tubular member 17 is threaded in the head 18 of the sleeve 19 which head rests on the base 20 of the elongated body portion to insure against the elements supported by the head 18 moving longitudinally 90 of the body portion. At the lower end of the sleeve 19 are flattened portions 21 constructed to receive a suitable wrench whereby the rotary movement will be imparted to the sleeve 19, tubular member 17, and feed sleeve 15.

Movable between the guide members 12 is a supporting screw 22 that moves through the feed sleeve 15 as clearly shown by Figure 3 of the drawings. In order that the 100 screw 22 will be held against rotary movement, a guide block 23 is provided which is of a width to operate between the guide members 12, the guide block 23 being however secured to the upper end of the screw 22. 105

Formed in the lower end of the feed screw 22 is a threaded socket 24 that accommodates the threaded extremity 25 of the polish

rod 26 so that the polish rod may be connected to the screw 22 to move vertically therewith.

From the foregoing it will be obvious that should it be desired to adjust the polish rod 26, it is only necessary to place a wrench on the flattened portion of the sleeve 19, rotating the tubular member 17 and feed sleeve 15, with the result that the feed screw 22 is moved longitudinally of the elongated body portion, thereby eliminating the necessity of removing the polish rod from its connecting member in order to make the adjustment.

15 I claim:

1. In a device of the character described, a body portion, a feed sleeve mounted within the body portion and adapted to rotate with respect thereto, a sleeve having a head 20 mounted for rotary movement at the base of the body portion, a tubular member connecting the sleeves, a screw movable through the feed sleeve, means for connecting the polish rod to the screw, and said screw

adapted to operate to move the polish rod 25 longitudinally of the body portion.

2. In a device of the character described, a body portion comprising spaced guided members, bearing blocks supported between the guide members and held against movement, a separable base on the guide members, said separable base embodying a support, a sleeve extending through the base and having a head adapted to rest on the base to support the sleeve, a tubular member threaded in the head, a feed sleeve at the upper end of the tubular member and engaging the bearing blocks, said feed sleeve having internal threads, a polish rod operating through the tubular member and 40 having a threaded portion adapted to be adjusted through the bearing blocks, and means for raising and lowering the body portion.

In testimony that I claim the foregoing 45 as my own, I have hereto affixed my signature.

LEONARD LOOP.
